TAP AND DIE COMPANY, OF MANSFIELD, MASSACHUSETTS, A CORPORATION OF
MASSACHUSETTS.

TAP-WRENCH.

977,691.

Specification of Letters Patent.

Patented Dec. 6, 1910.

Application filed June 3, 1910. Serial No. 564,750.

To all whom it may concern:

Be it known that I, CHARLES E. WILLIAMS, a citizen of the United States, residing at Mansfield, in the county of Bristol and State of Massachusetts, have invented a certain new and useful Improvement in Tap-Wrenches, of which the following is a specification, reference being had therein to the accompanying drawings.

10 Tap wrenches as usually made are formed with two jaws mounted in a head or case, one jaw of which at least is movable longitudinally toward and from the other jaw within the head or case, said other jaw usually 15 being stationary. The movable jaw is usually provided with a screw-threaded shank which is screwed into a tapped out socket in a handle, the socket end of said handle being threaded on its exterior periphery by a thread running in the opposite direction from the interior thread of the socket, said exterior thread 20 engaging with a tapped out tubular connection with the interior of the head so that by turning the handle, it will reciprocate the 25 said movable jaw in or out as desired according to the way the handle is turned. It is important that in moving the jaw in or out, the jaw should not be turned on its axis. It is also necessary that there should be an 30 opening in both sides of the head to the chamber in which the jaws are mounted in order to permit inserting the work between the mouths of the jaws. Sometimes heretofore the head has been made cylindrical, and 35 the chamber within the head has also been made cylindrical, the sides of the jaws being curved on the arc of a circle corresponding with the cross-sectional curve of the chamber of the head, and in such case, when the 40 handle is turned to move the jaw in or out, the jaw would also rotate with it unless some special means were used to prevent the 45 jaw from turning. Heretofore, when a cylindrical form of head is employed as above described, a common method has been to insert a pin or screw through the side of the head which engages with a longitudinal slot in the side of the jaw so as to prevent the 50 jaw from turning without interfering with its longitudinal movement. One objection to the cylindrical form of head is the inconvenience of getting the wrench down to the work. It is very desirable to have the sides of the head flattened and also the two oppo-

site faces of the jaws flattened correspondingly 55 so that the wrench can be brought down flat onto the work, the faces of the jaws coming out flush or nearly flush with the flat faces of the head. In wrenches heretofore constructed in which the sides of the wrench are 60 flattened and flat faced jaws have been used, the threads of the shank of the movable jaw and the handle have been exposed, and the fixed jaw had to be held in by a screw, and the jaws had no side support other than the 65 screw.

One object of the present invention is to provide such a construction as will enable the use of flat faced jaws with convex edges in combination with a flat faced head having 70 a rectangular work-opening for convenience of getting the wrench down to the work and formed with a chamber to inclose the shank and threaded connections of the movable jaw to protect them from grit and 75 dirt, and having concave guide-ways for the convex sides of the jaws, the flat walls of the chamber engaging the flat faces of the jaw so that the jaw is prevented from turning during its forward and back movement with- 80 out necessitating the use of pins or screws, the concave ways forming side supports for the jaws.

The invention will be fully understood from the following description taken in connection with the accompanying drawings, and the novel features are pointed out and clearly defined in the claims at the close of the specification.

In the drawings,—Figure 1 is a plan of 90 a wrench embodying the invention. Fig. 2 is a plan, similar to Fig. 1, partly in section, the ends of the handles being partly broken away. Fig. 3 is a side elevation of a wrench embodying the invention. Fig. 4 is a longitudinal section on line 4—4 of Fig. 1. Fig. 5 is a cross-section on line 5—5 of Fig. 1. Fig. 6 is a plan of the blank from which the head is formed. Fig. 7 is a side elevation of the head shown in Fig. 6. Fig. 8 is a section on line 8—8 of Fig. 6.

Referring now to the drawings,—1 represents the head of the wrench having the two opposite end tubular necks 2, 3, the neck 2 being internally screw-threaded to receive 105 the threaded end of the handle member 4 whose inner end forms a stop against which abuts the rear end of the fixed jaw 6. The

neck 3 is tapped out to receive the threaded end 7 of the handle 8 which operates the movable jaw 9, said movable jaw being formed with a threaded end 101 which screws 5 into the internally threaded end of the handle 8, the internal thread of the handle 8 being in the reverse direction from the exterior threaded portion 7. By rotating the handle the movable jaw is moved toward 10 or from the fixed jaw as desired. The particular construction or method of connection between the handle and the movable jaw, however, is not a part of the present invention and may be varied. The two jaws 15 6, 9, are flat on their top and bottom faces and are formed with convex opposite side edges 10, 10, which fit in concave grooves 11, 11, in the sides of the head 1. The top and bottom portions 12, 12, of the head 1 are 20 flat both on their exterior and on their interior faces, the interior faces fitting closely to the flattened faces of the jaws as close as is consistent with not impeding the in and out sliding movement of the jaw. Through 25 these top and bottom sides 12 of the head are rectangular openings 13 for gaining access to the jaws. The top and bottom walls of the chamber of the head 1 are preferably quite thin, and dip inward toward the middle, as shown in Fig. 4, in order that the faces of the jaws at their working ends may be flush with or project slightly outside of the work-opening. The cylindrical necks 30 spread and flatten to form the head intermediate the necks and form a chamber 15 within which the threaded end 101 of the shank of the movable jaw 9 is always enclosed, whether in its forward or back position. This chamber is clearly shown in 35 40 Fig. 4.

The flattened portions 16 at the ends of the work-opening 13 engage with some part of the flattened face of the jaw during the entire forward and back movement of the 45 jaw and thus prevent rotation of the jaw during the forward and back feeding movement. This close fit also prevents any dirt or grit getting into the chamber, and thereby by coming into contact with the threaded 50 shank of the jaw.

One feature of the invention relates to the method of constructing the wrench above described. If the head was in the first instance formed with a flattened top and bottom, it would be exceedingly difficult, if not impossible, to form the concave grooves 11 which it is desirable to obtain because of the flat walled chamber intermediate the cylindrically bored necks and the arc shaped 55 ways in the jaws which prevents insertion of any tool to bore out the curved grooves. In practical construction, therefore, it is necessary to have the said intermediate chamber made in the first place cylindrical so that 60 65 the cylindrical bore extends through both

the necks and the head and the said intermediate chamber. The blank is first formed solid, with the transverse work-opening and then drilled out lengthwise. A blank of such form after being bored or drilled out 70 is shown in Figs. 6, 7 and 8, in which the necks 2, 3, are each formed with tubular portions 17, 18, extending inwardly in continuation of the necks as far as the ends of the rectangular opening 13, the solid blank being drilled or bored from end to end forming the tubular passage through the necks 2, 3, and through the cylindrical projections 17, 18, and forming the concave grooves in the sides of the connected portion 19 corresponding with the concave grooves 11 in the sides of the head 1; then a former is inserted into the head, said former being of a size and shape corresponding with the two jaws combined, and the blank is subjected 80 to pressure to flatten down the rounded portions 17, 18, against the former into the thin flattened form of the completed wrench already described, after which the former is 85 withdrawn.

What I claim is:

1. A tap wrench having jaws which are formed with flattened faces and with side edges convexly curved in cross-section, one of said jaws being movable and having a threaded end, a head formed with a tubular cylindrical neck at each end, one of which receives the threaded end of the movable jaw, said head having a transverse work-opening and concave grooves in the sides thereof to 100 form ways for the jaws, said head having a flat walled chamber between the ends of said work-opening and the cylindrical neck, said chamber being formed at its inner end to correspond in cross-sectional contour with the cross-sectional contour of the jaws, and covering the rear ends of the jaws.

2. A tap wrench having a head formed with a transverse work-opening and concave ways for the jaws in the sides of said head, 110 in combination with jaws having convex sides which fit in said concave ways, said head and said jaws all having two flat faces.

3. A tap wrench having a head formed with a chamber for the jaws and having a transverse work-opening through the side walls of the chamber, said head having concave grooves in the opposite sides of the jaw-chamber to form ways for the jaws, said head having a non-cylindrical chamber between the said work-opening and the neck connecting therewith.

4. A tap wrench having a head formed with a chamber for the jaws and having a transverse work-opening through the side walls of the chamber, said head having concave grooves in the opposite sides of the jaw-chamber to form ways for the jaws, said head having a non-cylindrical chamber between the said work-opening and the cylind- 120 125 130

drical neck connecting therewith, the walls of said chamber having two flat faces which prevent the jaws from rotating.

5. A tap wrench having a head formed with a chamber for the jaws and having a transverse work-opening through the side walls of the chamber, said head having concave grooves in the opposite sides of the jaw-chamber to form ways for the jaws, a 10 tubular cylindrical neck at each end of the head, said head having a non-cylindrical chamber between the end of said work-opening and the cylindrical neck connecting therewith the walls of said chamber having two 15 flat faces which prevent the jaws from rotating, in combination with two jaws fitted in said grooved ways, one of said jaws being slidable longitudinally therein, and having a threaded end which extends into 20 one of said tubular necks, and means connected with said movable jaw whereby the said movable jaw may be moved longitudinally.

6. A tap wrench having a head formed with a chamber for the jaws and having a transverse work-opening through the side

walls of the chamber, said head having concaved grooves in the opposite sides of the jaw-chamber to form ways for the jaws, a 30 tubular cylindrical neck at each end of the head, said head having a non-cylindrical chamber between the end of said work-opening and the cylindrical neck connecting therewith, the walls of said chamber having two flat faces which overlap the rear ends of 35 the jaws, in combination with two jaws fitted in said grooved ways, one of which is slidable longitudinally therein and extends into one of said tubular necks, a handle having connection with said jaw whereby said 40 movable jaw may be moved longitudinally by rotating said handle, said flatted walls of the jaw-chamber engaging the said movable jaw to prevent its rotation while the handle is being rotated. 45

In testimony whereof I affix my signature, in presence of two witnesses.
